(12) **United States Design Patent** (10) Patent No.: **US D897,351 S**
(45) Date of Patent: **** Sep. 29, 2020**

(54) **DIGITAL SLIDE SCANNER**

(71) Applicant: **HAMAMATSU PHOTONICS K.K.**,
Hamamatsu-shi, Shizuoka (JP)

(72) Inventor: **Satoshi Watanabe**, Hamamatsu (JP)

(73) Assignee: **HAMAMATSU PHOTONICS K.K.**,
Hamamatsu-shi, Shizuoka (JP)

(**) Term: **15 Years**

(21) Appl. No.: **29/621,865**

(22) Filed: **Oct. 12, 2017**

(30) **Foreign Application Priority Data**

Apr. 13, 2017 (JP) 2017-007964

CLAIM

The ornamental design for a digital slide scanner, as shown and described.

DESCRIPTION

FIG. 1 is a front view of a digital slide scanner of the present invention.

FIG. 2 is a rear view thereof.

FIG. 3 is a top plan view thereof.

FIG. 4 is a bottom view thereof.

FIG. 5 is a right side view thereof.

FIG. 6 is a left side view thereof.

FIG. 7 is a perspective view thereof.

FIG. 8 is an enlarged view showing a portion of FIG. 1 defined by the lines 801-801 and 802-802.

FIG. 9 is an enlarged view showing a portion of FIG. 7 defined by the lines 901-901 and 902-902.

FIG. 10 is an enlarged cross-sectional view taken along the line 10-10 in FIG. 8 of a portion of FIG. 3 defined by the line 1001-1001.

FIG. 11 is an enlarged cross-sectional view taken along the line 11-11 in FIG. 1 of a portion of FIG. 3 defined by the line 1101-1101.

FIG. 12 is a front view of a second embodiment of the digital slide scanner of the present invention.

FIG. 13 is a rear view thereof.

FIG. 14 is a top plan view thereof.

FIG. 15 is a bottom view thereof.

FIG. 16 is a right side view thereof.

FIG. 17 is a left side view thereof.

FIG. 18 is a perspective view thereof.

FIG. 19 is an enlarged view showing a portion of FIG. 12 defined by the lines 1901-1901 and 1902-1902.

FIG. 20 is an enlarged view showing a portion of FIG. 18 defined by the lines 2001-2001 and 2002-2002.

FIG. 21 is an enlarged cross-sectional view taken along the line 21-21 in FIG. 19 of a portion of FIG. 14 defined by the line 2101-2101; and,

FIG. 22 is an enlarged cross-sectional view taken along the line 22-22 in FIG. 1 of a portion of FIG. 14 defined by the line 2201-2201.

The features shown in broken lines depict environmental subject matter only and form no part of the claimed design. The alternating long and short dashed lines indicate bounds of the claimed design and form no part thereof.
